UNDERWOOD TYPEWRITER COMPANY, OF NEW YORK, N. Y., A
CORPORATION OF NEW JERSEY.

TYPE-WRITING MACHINE.

No. 827,735.

Specification of Letters Patent.

Patented Aug. 7, 1906.

Application filed July 25, 1905. Serial No. 271,191

To all whom it may concern:

Be it known that I, EDWARD F. KUNATH, a citizen of the United States, residing in Jersey City, in the county of Hudson and State of New Jersey, have invented certain new and useful Improvements in Type-Writing Machines, of which the following is a specification.

This invention relates to the accent-key mechanism of those type-writing machines in which the ribbon is caused to vibrate at each type-stroke to cover and uncover the printing-point. In such machines the ribbon-vibrator is operated in the usual manner by a universal bar, and the latter is operated, as usual, by all the type-keys, including the accent-type keys; but each of the latter controls means for preventing the carriage from being fed by the operation of the universal bar, whereby it becomes practicable by striking one or more accent-keys before the ordinary type-key to secure the proper register of the accent or accents above or below the letter upon the written sheet.

In carrying out my present improvements I provide upon the universal bar of the well-known "Underwood" type-writing machine a trip which under normal conditions serves to transmit movement from the universal bar to the usual carriage-feeding mechanism, the latter being provided with an abutment which is engaged by said trip. To the accent key or keys, however, I connect means for intercepting said trip and causing it to swing to ineffective position, so that the universal bar is rendered incapable of moving the carriage-feeding mechanism out of normal position, and hence during the operation of the accent key or keys no feeding of the carriage is effected, although the ribbon is vibrated, as usual, by the universal bar.

In the accompanying drawings, Figure 1 is a perspective view of my improvements as applied to a universal bar and accent-type key in an Underwood front-stroke writing machine. Fig. 2 is a plan showing the trip on the universal bar as swung to an inoperative position and also illustrating how the trip may be controlled by any of a plurality of accent-type keys.

An accent-type 1 is fixed upon a type-bar 2, mounted upon a fulcrum-rod 3 and engaged by a bell-crank 4, the latter pivoted to

a lever 5, having an accent-key 6 and pivoted at its rear end at 7. The levers and bell-crank for the ordinary types are indicated at 8 and 9, respectively. A depression of any key carries down its lever and vibrates the bell-crank forwardly, thereby throwing the type-bar rearwardly, the type striking through a ribbon 10 against the front side of a platen. (Not shown.)

Each of the series of type-bars has a heel 11, which strikes a curved universal bar 12 and moves the same rearwardly, the universal bar being fixed upon a horizontal table or frame 13, which in said machine is suitably guided for rearward and forward movements. Upon said table 13 is usually fixed a slotted actuator 14, which engages a wrist 15, provided upon a short arm 16 of a lever 17, whereby the latter is caused to carry up and down a vibrator 18, through which is threaded the ribbon 10. The ribbon is vibrated at the actuation of all the type-keys, including the accent-key. Said universal-bar frame 13 is also utilized to effect the feeding of the platen-carriage, the latter including a rack 19, meshing with a pinion 20, connected to an escapement-wheel 21, with which coöperate the usual spacing and detent dogs 22 and 23, said dogs usually mounted upon an upright rock-arm 24. The backward movement of said rock-arm is effected in this instance by a trip 25, pivoted at 26 upon the top surface of the universal-bar frame 13 and having near its rear end a slot 27, which engages a stop-screw 28, said screw also preventing the rear end of the trip from lifting off from said frame 13.

The rear end or tip of the trip engages an abutment 29, projecting forwardly from the rock-arm 24, said abutment being in the form of a screw, so as to be adjustable, thereby to secure accurate and rapid feeding of the carriage. The trip under normal conditions engages said adjustable abutment at each rearward movement of a type-bar or of the universal-bar frame, so as to effect the usual feeding movement of the carriage. Said trip, however, is provided with an arm 30, and movable into the path of said arm is a stop or interceptor 31, mounted upon a rock-shaft 32 and normally out of use, as seen at Fig. 1. When, however, said rock-shaft is turned, the interceptor 31 is lifted into the path of

- the depending portion 33 of the trip-arm 30 and arrests the same, so that the rearward movement of the universal-bar frame 13 merely causes said trip to vibrate idly on its pivot 26 to the ineffective position. (Seen at Fig. 2.) Upon the return of the universal bar to normal position the trip is also restored to its normal position by a draw-spring 34, attached at one end to the arm 30 and at the other end to the frame 13.
- The movement of the interceptor 31 is effected by the accent-key 6, its lever 5 being provided with an upright rigid arm 35, connected by a link 36 to an arm 37, also fixed upon said rock-shaft 32. Upon depression of the key 6 the arm 35 swings forwardly about the pivot 7, and the link 36 is thrust forward, swinging the arm 37, thereby causing the shaft 32 to rock until the interceptor 31 reaches the position seen in dotted lines at Fig. 1 and full lines at Fig. 2. Upon relief of the key 6 from pressure it returns to normal position under the influence of the spring 38, and the interceptor 31 is returned by a spring 39, coiled about the shaft 32. The spring 34 returns the trip to normal position, permitting the ordinary type-keys thereafter to actuate the feeding mechanism 24 in the usual manner.
- At Fig. 2 are seen several accent-key levers 5, which are provided with arms 35 and links 36, the latter being slotted, as at 40, to engage pivots or pins 41 on the arms 37, whereby said shaft 32 may be rocked by any lever 35 independently of the other accent-key levers. Variations may be resorted to within the scope of my invention, and portions of my improvements may be used without others.
- Having thus described my invention, I claim—
1. In a type-writing machine, the combination with types, type-keys, and a carriage, of a universal bar operable by the type-keys, a ribbon-vibrator operable by said universal bar, a carriage-feeding mechanism, a trip operated by said universal bar and communicating movement to said carriage-feeding mechanism, and an interceptor movable by one of said keys into the path of said trip to move the latter to ineffective position; so that movement is not communicated from said universal bar to said feeding mechanism.
  2. In a type-writing machine, the combination with types, type-keys, and a carriage, of a universal bar operable by the type-keys, a ribbon-vibrator operable by the universal bar, a trip upon said universal bar, a normally idle interceptor for said trip, a type-key

controlling said interceptor, and a carriage-feeding mechanism operable by said trip; 60 said accent-type key being capable of moving said interceptor so that it will intercept said trip and cause the latter to become ineffective.

3. In a type-writing machine, the combination with types, type-keys, and a carriage, of a universal bar operable by the type-keys, a ribbon-vibrator operable by said universal bar, a trip pivoted upon said universal bar and having an arm, a normally idle interceptor for said arm, an accent-type key having means for moving said interceptor into effective position, a carriage-feeding mechanism, an adjustable abutment upon said carriage-feeding mechanism to be engaged by 75 said trip, and a returning-spring for said trip.

4. In a type-writing machine, the combination with types, type-keys, and a carriage, of a universal bar operable by the type-keys, a ribbon-vibrator operable by said universal 80 bar, a trip pivoted upon said universal bar and having an arm, a normally idle interceptor for said trip, a rock-shaft whereon said interceptor is mounted, an accent-type key, and connections from said accent-type key 85 to said rock-shaft.

5. In a type-writing machine, the combination with types, type-keys, and a carriage, of a universal bar operable by the type-keys, a ribbon-vibrator operable by said universal 90 bar, a trip pivoted upon said universal bar and having an arm, a normally idle interceptor for said trip, a rock-shaft whereon said interceptor is mounted, an accent-type key, a lever upon which said key is mounted, an arm fixed upon said lever, a link connected to the upper end of said arm, and an arm upon said rock-shaft to which said lever is connected.

6. In a type-writing machine, the combination with types, type-keys, and a carriage, of a universal bar operable by the type-keys, a ribbon-vibrator operable by said universal bar, a trip pivoted upon said universal bar and having an arm, a normally idle interceptor for said trip, a rock-shaft whereon said interceptor is mounted, an accent-type key, a lever upon which said key is mounted, an arm upon said lever, an arm upon said rock-shaft, and means for enabling the lever-arm 110 to operate the rock-shaft arm.
